SWITCH OPERATING MEANS

William J. Weinfurt, Wauwatosa, Wis., assignor
to McGraw Electric Company, a corporation
of Delaware

Application August 31, 1949, Serial No. 113,273

5 Claims. (Cl. 200—92)

1

This invention relates to a switch construction. Objects of this invention are to provide a switch construction which is so made that it will have not only a quick opening motion but also a quick closing motion and which is arranged for remote control through automatic means.

Further objects are to provide a switch construction which, though primarily intended for remote control, may nevertheless be operated manually in the event the remote control circuit becomes inoperative, and which, when operated manually, is free of any hampering or disturbing effect from the remote control or automatic operating means.

The switch forming the subject matter of this invention, though capable of many uses, is primarily intended for use as a capacitor switch for power factor correction. In switching capacitors, it is well known that when the capacitor is uncharged and is connected to a power line, the in-rush of current is enormous as the effect for an instant, at least, is the same as a dead short-circuit.

Various schemes have been tried to prevent damage to the switch mechanism due to this in-rush of current and this invention is designed to provide a switch which, when operated automatically, closes with such speed that there is substantially no damage to the contacts in switching a capacitor into the circuit.

An embodiment of the invention is shown in the accompanying drawings, in which:

Figure 1 is a view of the assembled switch unit.

Figure 2 is a sectional view approximately on the line 2—2 of Figure 1, such view showing the automatic operating means and not showing any portion of the switch located rearwardly of such means as viewed in Figure 2.

Figure 3 is a sectional view on the line 3—3 of Figure 1.

Figure 4 is a perspective view partly broken away showing a portion of the automatic operating means.

Figures 5 and 6 are sectional views on the lines 5—5 and 6—6 of Figure 4.

Figure 7 is a wiring diagram for the automatic control circuit of the switch.

Figure 8 is a plan view partly in section of the switch.

Figure 9 is a sectional view approximately on the line 9—9 of Figure 8, showing the switch closed.

Figure 10 is a sectional view approximately on the line 10—10 of Figure 8, showing the parts in switch open position.

2

Figure 11 is a sectional view showing the lower portion of the structure with the switch in open position.

Referring to the drawings, it will be seen that 5 the device comprises a housing or casing consisting of a lower casing member 1 and an upper cover or casing member 2 from which project the terminals 3. The device is supported from any suitable support by means of a bracket indicated 10 at 4 in Figure 1.

Switch means indicated generally by the reference character 5, see Figures 3, 9, 10 and 11 is interposed between the terminals 3. This switch means consists of an open-ended and open bottom casing 6 formed of insulating material and carrying stationary contacts 7 and pivotally carrying movable contacts 8. These movable contacts 8 are carried by levers 9 which are pivoted as indicated at 10 and which are electrically joined 15 by means of the conducting, resilient member 11. The inner ends of the levers 9 are slotted as indicated at 12 and a pin 13 carried by the insulating portion 14 of the vertically, reciprocable plunger fits within these slots and serves to actuate the 20 movable contacts when the plunger is raised or lowered. The upper end of the plunger is provided with a pair of spaced, metal extensions 15 between which the lower end of a connecting link 16 is pivoted. The upper end of the link 16 carries 25 a transversely extending pin 17, one end of which is pivoted in the arm 18 of a bell crank lever whose other arm is indicated at 19 in Figures 3 and 10. The pin 17 projects from the side of the link 16 opposite that of the lever 18 and is provided with a flat face 20, see Figures 3 and 10. The pin 17 is arranged to be latched by means of a 30 spring pressed latching lever or latch member 21 which is provided with a shoulder 22 below which the upper corner portion of the pin 17 is retained. The latch 21 is pressed in a clockwise direction as viewed in Figure 3 by means of a spring 23. It is provided with a lower foot or extension 24 which is adapted to be tripped or depressed by means hereinafter described.

45 The plunger 14 is urged upwardly by means of a pair of relatively heavy tension springs 25, see Figures 3, 9, 10, and 11. These tension springs have their lower ends hooked over a pin 26 and their upper ends hook into the arms of a bracket 50 member 27 carried by the cover 2 of the housing, see Figure 9. If desired, a bearing block which may be formed of insulating material and which is indicated at 28, may be employed to provide an extensive bearing surface for the pivot pin 29 of the latch lever 21 in view of the fact that a

relatively heavy, upwardly directed thrust is imparted to the latch lever 21 by means of the tension springs 25.

It is to be noted that the entire switch assembly is supported or suspended from the cover 2 and that the cover is removable from the lower housing 1. Also it is to be noted that the insulating bushings 30 extend downwardly and have sleeve-like portions 31 which project below the oil level indicated generally at 32.

A rock shaft 33 extends across the cover 2 and projects from opposite sides thereof. On one side it is provided with a manually, manipulatable, eyeleted lever 34 which is normally housed within a housing 35. This lever is hidden when the switch is closed and is exposed when the switch is open, its position under these two conditions being shown in dotted lines in Figures 3 and 10, respectively. The manually, manipulatable or hand lever 34 is rigidly attached to the rock shaft 33 externally of the housing and internally of the housing a lever 36 is also rigidly attached to the rock shaft. This lever is provided with a tripping cam or portion 37 which is adapted to engage the extension 24 of the latch 21 as shown in dotted lines in Figure 3 when the hand lever or manually, manipulatable lever 34 is pulled downwardly or, in other words, when the rock shaft 33 is rocked in a counter-clockwise directional manner as viewed in Figure 3. The tripping of the latch lever 21 allows the quick opening of the switch means due to the action of the tension springs 25.

When it is desired to close the switch manually, the lever 34 is pushed upwardly to the position shown in dotted lines in Figure 3. During this motion the lug 38 formed integrally with the lever 36 engages the under side of the arm 19 of the bell crank lever, thereby depressing its other arm 18 and moving such arm 18 from the position shown in Figure 10 to that shown in Figure 3, thereby resetting or closing the switch mechanism and latching it in closed position. A spring 39 is interposed between the levers 18 and 36 so as to normally hold the lug 38 in contact with the under side of the lever 19. However, when the hand lever 34 or manually, manipulatable member is pulled downwardly, the lug 38 moves away temporarily from the lever 19.

Remote control power means are provided for operating the switch mechanism, both to trip the switch and to close the switch. This mechanism is so constructed that it utilizes the quick trip or quick break of the switch hereinabove described and also, in itself, provides for the quick closing of the switch. This is highly desirable when the switch is employed as a capacitor switch as it is well known that when a capacitor is uncharged and is suddenly thrown across the line, that there is an enormous rush of current while the capacitor is being charged. However, having the switch closed with a snap action or quick action, no damage is done to the contacts.

The remote control or power driven switch operating means is indicated generally by the reference character 40 in Figure 2 and this mechanism is housed within a casing indicated generally by the reference character 41 in Figure 1, such casing being carried by the cover 2 of the main casing. This remote control mechanism consists of a unidirectional electric motor 42 which may be of any suitable type, such as a shaded pole motor for instance. This motor is connected by means of gearing, a part of which

only is shown in Figure 2, to a main gear 43. This main gear carries cams 44 and 45 which respectively operate the limit or selector switch mechanism indicated generally at 45 and the temporary holding switch mechanism indicated generally at 46. These switches are diagrammatically indicated in Figure 7.

The main gear 43 is provided with a unitary and rigid hub 47. The hub 47 rides loosely on the main power control rotary shaft 48. The rotary shaft 48 is provided with a projecting pin 49 which rides within a slot 50 formed in the hub 47 and together with the hub 47 forms an over-running clutch which has an over-running or free motion of approximately 180 degrees or, in other words, a half turn as is obvious from an inspection of Figures 4 and 6. The rotary shaft 48 is also provided with a second pin 51 which projects from one side only of the shaft and coacts with a slot 52 formed in the hub 53 of a crank or lever 54. The pin 51 and the slotted hub 53 form an over-running clutch providing an approximately free angular rotation of 180 degrees or one-half turn as is obvious from Figures 4 and 5. The main rotary shaft 48 also carries a rigidly attached crank 55. The crank 55 has an outwardly projecting crank pin 56 which is attached to one end of a tension spring 57. The other end of the tension spring 57 is attached to a fixed member 58 and the spring is so arranged that it is always under tension in all positions of the crank 55. This spring 57 serves the sole purpose of storing up energy when the power operated remote control means indicated generally at 40 is in action and for imparting a quick closing stroke to the switch mechanism during the closing stroke of the switch mechanism when the switch mechanism is power operated.

It is to be noted from Figures 8 and 9 that the rock shaft 33 extends from one side of the cover 2 to the other side thereof. This rock shaft projects into the casing 41 of the power driven and switch operating mechanism and a fragment of the shaft is shown in Figure 4. The shaft rigidly carries a lever 59, see Figures 2 and 4. In this connection, it is to be noted that Figure 4 is a more or less diagrammatic view to illustrate more clearly the coaction of the various parts of the power driven mechanism.

The arrangement is such that when either lever 59 or 34, see respectively Figures 4 and 3, is moved downwardly, that the switch is tripped and moves to open position with a snap action or quick motion. Also it is to be noted that when either the lever 59 or the lever 34 is moved upwardly, the switch is closed. When the lever 59 is moved upwardly by power means, it has a quick upward stroke which results in a quick closing stroke of the switch mechanism.

The operation of the power driven mechanism will now be described. When the motor 42, see Figure 2, is energized, it drives the main gear 43 in the direction indicated by the arrow in Figure 4 and consequently through the engagement of the pin 49 with one end of the slot 50 drives the shaft 48 in a counter-clockwise direction, thus rocking the crank 55 downwardly and storing energy in the tension spring 57, see Figure 4. In addition to this, the pin 51 through engagement with the end of the slot 52 rocks the lever 55 downwardly and thus serves to open the switch. The switch opens with a quick opening motion through the means hereinbefore described. The arrangement is such that when the

switch is opened by the power means, the crank 55 occupies the position shown in Figure 2, which is just to the left of dead center as viewed in Figure 2. In order to prevent reverse rotation of the main gear 43 and the gear train, a stop 60 carried by the main gear 43 is arranged to pass just beyond a latching spring finger 61, see Figure 2, so that the spring finger moves inwardly as viewed in Figure 2 and prevents reverse rotation of the main gear 43, although such gear is urged in that direction by the spring 57.

It is to be noted that the cranks 55 and 54 are in the position shown in Figure 4, almost opposite each other, that is to say, they lie in substantially the same plane. This is the relation of the cranks 55 and 54 during the power driven opening stroke of the switch. Obviously if the switch were manually opened, the lever 59, see Figure 4, would merely rock downwardly and thus depress and rock the lever or crank 54 downwardly without imparting any rotation to the shaft 48 as the slot 52 would allow rotation of the hub 53 of the lever 54 freely without engagement of the pin 51 by the hub 53. During power opening, however, the pin 51 engages the now upper end of the slot 52 as shown in Figures 4 and 5, such figures being line drawings.

Assume that the switch has been opened by the remote control power means. The crank 55 extends downwardly but has not yet passed dead center as shown in Figure 2 and the crank or lever 54 similarly has not quite passed dead center as it is substantially opposite the lever 55 under these conditions. However, upon energization of the motor 42 to close the switch such motor rotates in the same direction as that in which it previously rotated and consequently drives the main gear 43 in a counter-clockwise direction and rocks the crank 55 past dead center. The spring 57, see Figure 2, when carried from the position shown in Figure 2 to the right of dead center as viewed in such figure, causes a quick counterclockwise rotation of the crank 55 and consequently causes a quick counterclockwise rotation of the crank 54. In view of the fact that the crank 54 is connected to the lever 59, see Figure 4, by means of the link 62, it is obvious that the lever 59 is rocked upwardly with a quick motion and consequently the switch means is closed with a quick motion.

It is to be noted also that after the switch has been closed by the power means, that the pin 51, see Figure 4 and Figure 5, will be free to move in the slot 52. Consequently, if it now becomes desirable to open the switch manually, such opening may be freely accomplished as there is no hindrance to forward rotation of lever 54.

It is to be noted particularly that the switch may be manually opened or closed as previously described without any hindrance to such operations due to the presence of the power driven remote control operating mechanism.

It is to be understood that the motor 42 is a unidirectional motor and that it is controlled in any suitable manner as by means of a contact making voltmeter or other suitable means indicated generally by the reference character 63, see Figure 7. Also it is apparent that the selector and limit switch means 45 will allow the motor 42 to rotate the main gear 43 selectively in half revolutions. Further than this, it is to be noted that the holding switch means indicated generally at 46 is so arranged that it temporarily closes a circuit which bridges both the selector or limit

switch means 45 and the contact making voltmeter means 63. This bridging through the action of the holding switch 46 occurs a brief instant after the contact making voltmeter 63 has initiated the rotation of the motor 42 and continues until the motor has driven the main gear 43 through its selected half revolution. At the time that the half revolution of the main gear 43 is completed the bridging switch means 46 automatically opens due to the arrangement of the cams 44 carried by the main gear 43. In this way it is possible to insure the complete half revolution of the main gear 43 although the contact making voltmeter may close only a relatively brief interval and may again open due to jarring, for instance, or for other causes.

It is to be noted particularly that this invention provides absolute freedom for the manual operation of the switch independently of any action of the power driven remote control switch operating means.

Further than this, it is to be noted particularly that a simple unidirectional, nonreversing type of electric motor may be employed.

The independence of the manual operation of the switch permits its manual operation in the event the remote control circuit becomes defective from any cause whatsoever and thus allows for the emergency operation of the apparatus without any alteration of the electrical connections or of the mechanism whatsoever.

Although this invention has been described in considerable detail, it is to be understood that such description is intended as illustrative rather than limiting, as the invention may be variously embodied and is to be interpreted as claimed.

I claim:

1. A switch construction comprising switch means, a rock shaft operatively connected to said switch means for causing opening and closing of said switch means when rotated in switch-opening and switch-closing directions, respectively, manual means connected to said shaft and power driven means each operatively coupled to said shaft for rotating said shaft in either direction, said power driven means including quick motion mechanism for imparting a quick rotation to said shaft in a switch-closing direction and including a second shaft rotated in one direction only by said power driven means and connected with said rock shaft by crank and link mechanism and including coupling means connecting said rock shaft and said power driven means for allowing movement of said manual means independently of said power driven means.

2. A switch construction comprising switch means, a rock shaft operatively connected to said switch means for causing opening and closing of said switch means when rotated in switch-opening and switch-closing directions, respectively, manual means connected to said shaft and power driven means each operatively coupled to said shaft for rotating said shaft in either direction, said power driven means including quick motion mechanism for imparting a quick rotation to said shaft in a switch-closing direction and including a second shaft rotated in one direction only by said power driven means and connected with said rock shaft by crank and link mechanism and including coupling means connecting said rock shaft and said power driven means for allowing movement of said manual means independently of said power driven means, said manual means and said power driven

7 means being operable independently of each other.

3. A switch construction comprising switch means biased towards open position, a rock shaft operatively connected to said switch means for closing said switch means, a trip normally restraining said switch means against opening motion, means operated from said rock shaft for tripping said trip, a power driven rotary shaft, 10 motor means for rotating said shaft through approximately half revolutions, selector switch means for controlling the rotation of said power shaft through half revolutions, a first crank carried by said rock shaft, spring means connected to said first crank and being arranged to store energy when said first crank is moved through a first half revolution, an overrunning clutch having approximately a one-half revolution free rotation operatively interposed between said motor means and said shaft, a second crank carried 15 by said shaft, a second overrunning clutch interposed between said second crank and said shaft and having approximately a half revolution free rotation, and link-work mechanism operatively connecting said second crank and said rock shaft.

4. A switch construction comprising switch means biased towards closed position, a rock shaft operatively connected to said switch means for closing said switch means, a trip normally restraining said switch means against opening motion, means operated from said rock shaft for tripping said trip, a power driven rotary shaft, 30 motor means for rotating said shaft through approximately half revolutions, selector switch means for controlling the rotation of said power shaft through half revolutions, a first crank carried by said rock shaft, spring means connected to said first crank and being arranged to store energy when said first crank is moved through a first half revolution, an overrunning clutch having approximately a one-half revolution free rotation operatively interposed between said motor means and said shaft, a second crank carried 35 by said shaft, a second overrunning clutch interposed between said second crank and said shaft and having approximately a half revolution free rotation, link-work mechanism operatively connecting said second crank and said rock shaft, and manually operable means for opening and closing said switch means when moved in opposite directions, carried by said rock-shaft, said overrunning clutch means allowing manual operation of said switch means independent of said 50 55

motor means and allowing said manually operable means to be moved in either direction independently of said motor means.

5. A switch construction comprising switch means, a rock shaft operatively connected to said switch means for causing opening and closing of said switch means when rotated in switch-opening and switch-closing directions, respectively, manual means and power driven means each operatively coupled to said rock shaft for independently rotating said rock shaft in either direction, said power driven means constituting a quick motion device and including a revolute shaft, a power driven member mounted on said revolute shaft and connected therewith by a first lost motion means, said revolute shaft having a crank and being connected therewith by a second lost motion means, said crank being operatively connected to said rock shaft, said first and second lost motion means having a connection with said shaft to allow said revolute shaft to lead said power driven member and said crank to lead said revolute shaft each approximately a half revolution, respectively, a second crank rigid with said revolute shaft, and a spring operatively connected to said second crank and biasing said crank towards a predetermined position on one side of said revolute shaft.

WILLIAM J. WEINFURT.
